UNITED STATES PATENT OFFICE.

PAUL FRANÇOIS MARC ALBERT FONTANA, OF CLUSES, FRANCE, ASSIGNOR TO SOCIETE DES APPAREILS MEPHISTO JULES MANFREDI AND CIE., OF CLUSES (HAUTE-SAVOIE), FRANCE.

VULCANIZER.

Application filed November 18, 1925, Serial No. 69,882, and in France June 25, 1925.

This invention relates to an apparatus lighted and heated automatically for the vulcanization of air-tubes for the tires of motor cars, motor-cycles and cycles and concerns repairing elements each comprising a rubber patch impregnated with sulphur and arranged under a metal cup containing a washer of nitrate of potash, these elements being characterized by the fact that they are provided over their entire upper surface with ignition products, such as nitrate of potash and amorphous phosphorus, this cup being closed by a varnished piece of cardboard impregnated with paraffin and which covers the said cup.

The invention is illustrated by way of example only, in the accompanying drawing in which:

Fig. 1 is a sectional view showing a repairing element.

Fig. 2 is a corresponding plan view.

Fig. 3 is a view showing the method of utilization.

Fig. 4 is a section of the press serving to apply the repairing element on the member to be repaired and to light it.

As illustrated in the drawing, the repairs are effected by means of elements such as illustrated in Figs. 1 and 2. Each of these elements comprises a rubber patch *a* made of pure Para rubber, having the required shape: round, oval, etc. This rubber patch contains a certain quantity of sulphur so that it can be vulcanized. This patch is secured by means of glue to the under side of a metal cup *b* having the same shape. Its lower face is covered with a piece of canvas *c* which protects it before use.

Within the cup 3 is placed a composition capable of burning during a predetermined time to produce a rise in temperature also predetermined. This composition is, preferably, obtained by impregnating a washer of straw-board *d* with nitrate of potash and by covering the entire surface with nitrate of potash and amorphous phosphorus. Before use, this composition is sheltered from the air by a piece of cardboard *e* covered with paraffin and varnished. This piece of cardboard *e* protects the composition against moisture and oxidation.

The member to be vulcanized is applied against the air tube to be repaired by means

of the press illustrated, which comprises a yoke *f* provided at its base with a small table *g*.

The clamping is produced by means of a claw *i* which carries a handle *l* serving to operate it.

The interior of the screw is hollow and contains a striker *m* terminated by a knob *m'* pressing, through a shoulder *n*, on a spring *o*; the lower striated part passes in front of spark producing elements, preferably ferro-cerium stones *p* contained in two conduits *q* secured on the lower part of the screw *k*. The stones *p* are pushed by springs *r* adjusted by screws *s*.

The operation is as follows:

For effecting a repair, the damaged portion of the air tube *v* (Fig. 3) or other member to be repaired, is cleaned. The canvas covering washer *c* is removed from a patch of the required shape, as well as the piece of cardboard *e* impregnated with paraffin. The cup and the patch are placed on the air tube and the whole is inserted in the press, as shown in Fig. 3; the screw is acted upon for suitably clamping the cup.

These preparations being effected, a blow is struck on the striker *m*. The sparks produced ignite the composition which burns during the required time by producing the temperature necessary for ensuring the vulcanization.

Immediately after cooling, the repaired air tube or other member can be used.

It will be noted that, as the entire surface of the patch is covered with phosphorus, whatever may be the point of impact, the ignition is ensured.

The arrangements described above are given by way of example only; all the details of execution and of realization, the forms, materials and dimensions can be varied without departing thereby from the principle of the invention.

Claims:—

1. A repairing element for a vulcanizer lighted and heated automatically, comprising a metal cup, a rubber patch impregnated with sulphur and secured to the under face of this cup, a combustible composition within the cup, and ignition means covering said composition over its entire surface.

2. A repairing element for a vulcanizer

lighted and heated automatically, comprising a metal cup, a rubber patch impregnated with sulphur and secured to the under face of this cup, a combustible composition in the cup, ignition means covering this composition over its entire surface, and means for sheltering said composition from the air.

3. A repairing element for a vulcanizer lighted and heated automatically, comprising a metal cup, a rubber patch impregnated with sulphur and secured to the under face of this cup, a washer of straw-board impregnated with nitrate of potash within the cup and ignition means covering said composition over its entire upper surface.

4. A repairing element for a vulcanizer lighted and heated automatically, comprising a metal cup, a rubber patch impregnated with sulphur, and detachably secured to the under face of this cup, a combustible composition within said cup, phosphorus covering this composition over its entire surface.

5. A repairing element for a vulcanizer lighted and heated automatically, comprising a metal cup, a rubber patch impregnated with sulphur and detachably held to the under face of this cup, a washer of straw-board impregnated with nitrate of potash, and phosphorus covering said composition over its entire surface.

6. A repairing element for a vulcanizer lighted and heated automatically, comprising a metal cup, a rubber patch impregnated with sulphur and adhesively secured to the under face of this cup, a combustible composition within the cup, ignition means covering said composition over its entire surface, and a piece of cardboard impregnated with paraffin overlaying said composition for sheltering the same from the air.

The foregoing specification of my "vulcanizer" signed by me this 6th day of November 1925.

P. F. M. A. FONTANA.
